UNITED STATES PATENT OFFICE

112,326

DESIGN FOR A HAT ORNAMENT OR SIMILAR ARTICLE

Samuel Antenberg, Brooklyn, N. Y.

Application May 3, 1938, Serial No. 76,941

Term of patent 3½ years

To all whom it may concern:

Be it known that I, Samuel Antenberg, a citizen of the United States, residing at 3031 Brighton 14 St., Brooklyn, in the county of Kings and State of New York, have invented certain new, original, and ornamental Design for a Hat Ornament or Similar Article, of which the following is a specification, reference being had to the accompanying drawing, forming part thereof.

I claim:

The ornamental design for a hat ornament or similar article, as shown.

SAMUEL ANTENBERG.
